[57] CLAIM

The ornamental design for a plastic container cutting, opening and closing tool, as shown and described.

DESCRIPTION

FIG. 1 is a front elevational view of a plastic container cutting, opening and closing tool, showing my new design;

FIG. 2 is a top plan view thereof;

FIG. 3 is a perspective view showing the tool of FIG. 1; the broken line showing of the container and the lid is for illustrative purposes only and forms no part of the claimed design;

FIG. 4 is a top perspective view taken from the right side thereof;

FIG. 5 is a perspective view taken from the top left side thereof; and,

FIG. 6 is a perspective view taken from the bottom right side thereof.

FIG. 3

FIG. 4

FIG. 5

FIG. 6
